UNITED STATES PATENT OFFICE.

GEORGE SAMUEL ANDRES, OF CHICAGO, ILLINOIS.

CYLINDER CONSTRUCTION.

1,413,372.

Specification of Letters Patent. Patented Apr. 18, 1922.

Application filed October 6, 1919. Serial No. 328,870.

To all whom it may concern:

Be it known that I, GEORGE SAMUEL ANDRES, a citizen of the United States, and a resident of the city of Chicago, in the county of Cook and State of Illinois, have invented certain new and useful Improvements in Cylinder Construction; and I do hereby declare that the following is a full, clear, and exact description of the same, reference being had to the accompanying drawings, and to the numerals of reference marked thereon, which form a part of this specification.

This invention relates to cylinder construction, and, although not restricted to such use, is particularly adapted for internal combustion engines.

Frequently it is desirable to construct the cylinder of different material from the parts adjacent thereto, such as the cylinder head and crank case. Thus the cylinder may advantageously be composed of steel, the cylinder head of cast iron and the crank case of aluminum or other metal.

Further, the cylinder of an internal combustion engine wears unequally not only circumferentially owing to lateral pressure of the connecting rod, but also longitudinally since the piston and piston rings do not traverse the whole surface of the cylinder.

It frequently happens that the cylinder becomes cracked owing to freezing of the water in the water jacket or other causes, in which case the entire cylinder, cylinder head and water jacket have to be replaced.

In other cases the cylinder is of unequal thickness due to imperfect centering of the cores for the bore of the cylinder and the water jacket respectively.

The usual practice of casting the cylinders and water jackets as a unit involves expensive grinding and other machines for boring the cylinder and forming the valve seats and other parts.

It is an object, therefore, of the present invention to provide an engine having a cylinder which is separable from both the cylinder head and the crank case, and in addition may be adjusted angularly through say 90° with respect to these parts and preferably also reversed in position end for end relatively to the cylinder head and crank case.

Another object of the invention is to provide a cylinder whose expansion and con-

traction under varying temperatures is not influenced by cast-on water jackets.

A further object of the invention is to provide a cylinder capable of being machined inside and out so that the cylinder walls may be made of uniform predetermined thickness throughout.

It is also an object of the invention to provide a removable cylinder tube with a self-sealing joint between the tube and the cylinder head and crank case.

An additional object of the invention is to provide a cylinder with flanges or other projections on its outer surface for increasing the area in contact with the water in the water jacket.

Other and further important objects of this invention will be apparent from the disclosures in the specification and drawings.

The invention (in a preferred form) is illustrated in the drawings and hereinafter more fully described.

On the drawings:

Figure 1 is a central vertical section through a part of an internal combustion engine embodying the features of the present invention.

Figure 2 is a side elevation of the cylinder tube.

Figure 3 is a section on the line 3—3 of Figure 1.

Figure 4 is a section on the line 4—4 of Figure 1.

As shown on the drawings:

The invention is illustrated in connection with an internal combustion engine of the high compression type having a single pressure-sustaining valve 1, and two auxiliary valves 2 and 3, for the inlet and exhaust respectively. The main valve 1 is opened at the beginning of the exhaust period and held open until the end of the intake period. The exhaust valve is held open during the exhaust period and then closed when the inlet valve is opened.

The valves are arranged in a cylinder head 4, detachably mounted on the top of a cylinder tube 5. The lower end of this tube in turn rests upon the crank case 6.

Annular tongues 7 are formed on each end of the cylinder tube for engagement with corresponding grooves in the crank case and cylinder head. Suitable packing material is placed in these grooves to provide a tight joint.

The cylinder head is drawn down towards the crank case by means of bolts 8 threaded into or otherwise suitably secured to the crank case and passing through apertures in the cylinder head. By tightening the nuts on these bolts the cylinder tube may be firmly gripped between the cylinder head and the crank case, while at the same time the tongues 7 are forced into their corresponding grooves to compress the packing therein.

Each end of the cylinder tube is of the same form and dimensions so that it may be reversed end for end to equalize wear and for other reasons. Further, since the lateral pressure of the connecting rod causes the cylinder to wear more along its plane of movement than along the vertical plane transverse thereto, it is desirable to turn the cylinder tube through 90° to equalize such wear. This may be readily accomplished by loosening the nuts on the bolts 8, rotating the cylinder tube through the desired angle and then tightening the nuts again.

Around the cylinder tube is a member 9 forming the outer part of the water jacket of the cylinder. In a single cylinder construction it is circular, as shown, but in a multi-cylinder engine it is conveniently elongated to enclose all the cylinders. The upper and lower ends of the tube 9 are arranged to fit into grooves in the cylinder head and crank case respectively. Packing 35 is placed in these grooves so that, when the parts are clamped together by the bolts 8, tight joints are formed. Corrugations 10 are formed in the tube 9 to allow for expansion and contraction due to changes in temperature therein. For increasing the surface in contact with the water in the water jacket suitable projections, such as flanges or ribs 11, may be formed on the outside of the tube 5.

In view of its complicated form, the cylinder head is preferably formed of cast iron or aluminum with valve seats of other suitable material, while to lighten the construction the crank case may conveniently be formed of aluminum or an aluminum alloy. 50

The cylinder tube is preferably steel to provide the necessary strength and resistance to wear coupled with relatively slight thickness to enable it to be kept cool by the water-jacket. 55

I am aware that numerous details of construction may be varied through a wide range without departing from the principles of this invention, and I therefore do not purpose limiting the patent granted 60 otherwise than necessitated by the prior art.

I claim as my invention:

A water-cooled internal combustion engine comprising a cylinder, cooling flanges on the outer surface thereof, a cylinder head, a crank case, tongue and groove connections between the cylinder and both the cylinder head and crank case, said cylinder being thereby adapted to be reversed in position relatively to the cylinder head and 70 crank case and having a removable water jacket therearound with a larger cooling space at the top than at the bottom connected to the cylinder head and the crank case by tongue and groove connections and 75 provided with horizontal corrugations to provide additional cooling surface, and means for clamping the cylinder head and crank case together in position on the cylinder with the water jacket therearound. 80

In testimony whereof I have hereunto subscribed my name in the presence of two subscribing witnesses.

GEORGE SAMUEL ANDRES.
